WARE.

CYLINDER-LINER.

1,081,257.

Specification of Letters Patent.

Patented Dec. 9, 1913.

Application filed May 12, 1910. Serial No. 560,795.

To all whom it may concern:

Be it known that I, CARL G. SPRADO, a citizen of the United States, residing at Milwaukee, in the county of Milwaukee and State of Wisconsin, have invented a certain new and useful Improvement in Cylinder-Liners, of which the following is a specification.

This invention relates to improvements in the construction of cylinders for engines, and more particularly to the construction of liners or bushings and to means for inserting same within the cylinders.

The object of the invention is to provide a simple and efficient means for attaching liners to the interior walls of the cylinders.

In the manufacture of cylinders, such as pumping, gas or steam engine cylinders, it has been found difficult, especially on the larger sizes, to obtain cast metal on the interior working surfaces of the cylinders, which is entirely free from slag and blow-holes. It is moreover often desirable to make the major portion of the cylinder of one metal and to have the working surfaces thereof lined with a different material. It therefore becomes necessary to counterbore the cylinder and insert a liner which is devoid of defects or which is composed of a desirable material. Such inserted liners are usually shrunk into position within the cylinders, and it is to the construction and insertion of these liners that the present invention has particular relation.

A clear conception of several embodiments of the invention can be obtained by referring to the accompanying drawing in which like reference characters designate the same or similar parts in like or different views.

Figure 1 is a central, vertical section of an engine cylinder showing a liner constructed according to the invention inserted therein. Fig. 2 is an enlarged, fragmentary, central, vertical section of the cylinder and liner shown in Fig. 1, showing the relative positions of these members before shrinking. Fig. 3 is a central, vertical section of a fragment of an engine cylinder showing a modification of the liner shown in Fig. 1 inserted therein.

The cylinder 1 has a central, one-piece, circumferentially continuous bearing wall 2 and may be of any desirable construction, depending upon the type of engine with which it is to be associated. The shell or

liner 3, see Fig. 1, is cylindrical in form, having a through bore against which the engine piston, not shown, normally coacts. The liner 3 has a section of enlarged outside diameter near its middle, forming an annular flange 4. This flange 4 coacts with a corresponding groove in the cylinder wall 2 and divides the liner 3 into the two end portions 5, 6, which are adjacent the flange 4. The portion 5 has a larger outside diameter than that of the portion 6, the wall 2 being bored correspondingly at the surfaces of coaction of the portions 5, 6, therewith, see Figs. 1 and 2. The diameters of the portions 5, 6, are determined by the material of which the liner 3 and cylinder wall 2 are constructed, by the temperature to which they are cooled and heated during shrinking, and by the diameter of the bore of the cylinder liner. These diameters must, however, be such that the relative positions of cylinder wall 2 and liner 3 are as shown in Fig. 2, with the members cooled and heated respectively, preparatory to shrinking. The shrinkage space 7 is practically constant throughout the length of the liner 3, the outside diameter of the flange 4 being slightly less than the internal diameter of the wall 2 at the section thereof along which the end portion 5 normally coacts. The outside diameter of the flange 4 is, however, slightly larger than the internal diameter of the wall 2 at the section thereof along which the end portion 6 normally coacts, so that the liner 3 cannot pass entirely through the interior bore of the wall 2, and can be inserted into position from one end of the cylinder 1 only.

In the modification, see Fig. 3, the end portions 51, 61, of the liner 31, have equal outside diameters. The cylinder wall 2 has a through bore except for an internal flange 8 at one end of the liner 31, and the recess which receives the flange 4 of the liner 31.

In constructing the cylinder 1, the wall 2 is bored to three diameters, which are slightly smaller than the corresponding outside diameters of the portions of the liner 3 which are intended to coact therewith after shrinking. The outer surfaces of the liner 3 having been turned to the proper diameters, the liner 3 is provided with false heads at its ends, and the chamber formed by the liner and false heads is filled with a cold medium, such as water, which causes

the liner 3 to contract slightly. The cylinder wall 2 is then provided with a heating jacket, such as steam of high temperature, which causes the cylinder wall 2 to expand. 5 The liner 3 is then dropped into the bore of the cylinder walls 2, the relative positions of the members being as shown in Fig. 2, that is, with the annular clearance space 7 between them. The cold medium within 10 the liner 3 is withdrawn while, at the same time, the heating jacket of the wall 2 is removed, causing the liner 3 and wall 2 to expand and contract respectively toward each other until the adjacent surfaces coat, thus 15 completing the shrinking process. It will be noted that during the shrinking, the portions 5, 6, of the liners as well as the corresponding portions of the cylinder walls 2, will expand and contract longitudinally as 20 well as on their respective diameters. By forming the anchoring flange 4 near the center of the liner, the portions 5, 6, are allowed to expand away from the center, while the wall portion corresponding thereto 25 contracts toward the flange 4. With such relative expansion and shrinkage of the members, an ideal fastening of the liners 3 is obtained, since the relative movement of the members is away from the center rather 30 than from one end of the cylinder. The use of the locking or anchoring flange 4 at the central portion of the liner 3 moreover 35 forms a simple and efficient means for securing the liner 3 against end motion after shrinkage.

In the modification, see Fig. 3, the operation of shrinking the liner 31 into the cylinder walls 2 is the same as above described for the preferred form. In this case, how-

ever, the expansion of the liner 31 and the shrinkage of the walls 2 is away from and toward one end of the liner 31, respectively, due to the abutment of the liner 31 against the flange 8 of the cylinder just before shrinking. The locking or anchoring flange 4 of the modification is formed at the center of the liner 31, thus providing a similar means for preventing end movement of the liner 31 after shrinkage.

It should be understood that it is not desired to be limited to the exact details of construction shown and described, for obvious modifications will occur to a person skilled in the art.

It is claimed and desired to secure by Letters Patent,—

1. In a cylinder, a liner having an outer flange and portions of different diameters immediately adjacent said flange and on either side thereof, and a circumferentially continuous wall member locked to said liner and closely fitting the portions of said liner of different diameters.

2. In a cylinder, a liner having an outer flange and portions of different diameters immediately adjacent said flange and on either side thereof, and a circumferentially continuous wall member locked to said liner and closely fitting the portions of said liner of different diameters, said liner being insertible within said wall member through one end thereof only.

In testimony whereof, I affix my signature in the presence of two witnesses.

CARL G. SPRADO.
